(57) **CLAIM**

The ornamental design for a placket with inverse fasteners, as shown and described.

DESCRIPTION

This application contains at least one drawing executed in color. Copies of this application with color drawing(s) will be provided by the Office upon request and payment of the necessary fee.

FIG. 1 is a front view of an outer portion of an embodiment of a placket with inverse fasteners showing my new design; FIG. 2 is a rear view of the outer portion and a front view of an inner portion of FIG. 1, wherein the placket with inverse fasteners is open;

FIG. 3 is a first side view of a portion FIG. 2;

FIG. 4 is a second side view of a portion of FIG. 2;

FIG. 5 is a rear view of the outer portion and a front view of the inner portion of FIG. 1, wherein the placket with inverse fasteners is mostly closed;

FIG. 6 is a top view of FIG. 3;

FIG. 7 is a top view of FIG. 4;

FIG. 8 is an enlarged view of the inverse fasteners in FIG. 2;

FIG. 9 is an enlarged view of the inverse fasteners in FIG. 5;

FIG. 10 is a front view of an outer portion of a different embodiment of a placket with inverse fasteners showing my new design;

FIG. 11 is a rear view of the outer portion and a front view of an inner portion of FIG. 10, wherein the placket with inverse fasteners is open;

FIG. 12 is a first side view of a portion of FIG. 11;

FIG. 13 is a second side view of a portion of FIG. 11;

FIG. 14 is a rear view of the outer portion and a front view of the inner portion of FIG. 10, wherein the placket with inverse fasteners is mostly closed;

FIG. 15 is an enlarged view of the inverse fasteners in FIG. 11; and,

FIG. 16 is an enlarged view of the inverse fasteners in FIG. 14.

The short-dash broken lines form no part of the claimed design. The claimed design extends to the long-dash broken line boundaries in FIGS. 2, 4, 5, 7-9, 11, and 13-16, but does not include the boundary.

No claim is made to the thickness of the inverse fasteners or the color of the inverse fasteners apart from the red front surfaces of the inverse fasteners.
